UNITED STATES PATENT OFFICE.

VERNON DURBIN, OF NEWTON, MASSACHUSETTS, ASSIGNOR TO THE HOLTEER-CANOT ELECTRIC COMPANY, OF ROXBURY, MASSACHUSETTS, A CORPORATION OF MASSACHUSETTS.

TELEPHONE RECEIVER.

Application filed March 19, 1923. Serial No. 625,942.

To all whom it may concern:

Be it known that I, VERNON DURBIN, a citizen of the United States, residing at Newton, in the county of Middlesex and State of Massachusetts, have invented certain new and useful Improvements in Telephone Receivers; and I do hereby declare the following to be a full, clear, and exact description of the invention, such as will enable others skilled in the art to which it appertains to make and use the same.

The present invention relates to an improvement in telephone receivers.

The object of the invention is to reorganize and improve the construction of such receivers for the purpose of facilitating the manufacture and reducing the cost. To the above ends the present invention consists in the receiver hereinafter described and particularly defined in the claims.

In the accompanying drawings illustrating the preferred form of the invention, Fig. 1 is a perspective view of one of the laminations of a magnet core; Fig. 2 is a perspective view of a magnet core built up of twelve laminations; Fig. 3 is a plan and elevation of a spool top; Fig. 4 is a plan and elevation of a core head insulator; Fig. 5 is an elevation of a magnet core looking at the edges of the laminae; Fig. 6 is an elevation taken at right angles to the plane of Fig. 5; Fig. 7 is a plan and elevation of a core head or spool bottom; Fig. 8 is a bottom plan and end view of the core shoe or back piece of a magnet; Figs. 9 and 10 are front and side elevations of the magnet core, spool heads, core head insulator and core head and core shoe assembled; Figs. 11 and 12 are side and front elevations respectively of a magnet spool and winding assembly; Fig. 13 is a bottom plan of a pair of magnet spools; Fig. 14 is a side elevation of the same; Fig. 15 is a top plan of the same; Fig. 16 is a perspective view of one of the permanent magnets; Fig. 17 is a perspective view of the magnet cover; Figs. 18, 19 and 20 are, respectively, a top plan, a side elevation and a bottom plan of the terminal block; Fig. 21 is a sectional elevation of the receiver taken on the line 21-21, Fig. 22, with the ear piece and diaphragm removed; Fig. 22 is a plan view of the receiver with the ear piece and diaphragm; and Fig. 23 is a sectional elevation taken on the line 23-23, Fig. 22.

The illustrated embodiment of the invention is described as follows, and for convenience the description will follow the order of assembly of the elements and the method practiced in assembling the receiver so as to present a graphic description of the receiver, its component elements, method of manufacture and assembly.

The core laminae or laminations 50 are stamped with the shape shown in Fig. 1 from sheet silicon iron. Each lamina has an enlarged head 51 and a reduced foot 52. Twelve of these assembled together make up the complete core 53. These separate loose laminae gathered together are first thrust through the hole in the spool top 54, which hole 55 is of the size of the cross section of the body of the core 53. This spool top is pushed up against the under side of the head 56 or pole piece of the built up core and serves temporarily to unite the layers of the core into a temporarily held body. This spool top is made of bakelite impregnated duck. Next there is applied the core head insulator 57 made of empire cloth, being a varnished insulating cloth. This core head insulator is shown in temporary position in Figs. 5 and 6. Next the core head or spool bottom 60 provided with a hole 61 is pushed on to the core, the hole 61 being the same size as the holes in the core head insulator and spool top. This core head is provided with two brass eyelets 62 inserted in the corners of the head, as shown in Fig. 7, for a purpose hereinafter described. The core shoe 63, made of soft iron, is provided with a core hole 64 and a screw hole 65. It is applied to the reduced end or foot piece 66 of the core 53, the reduced end 66 entering the hole 64, and fitting it snugly, thereby acting to hold the laminations of the core together. The bottom side of the hole in the core shoe shown in Fig. 8 is counterbored at 67, and after the foot piece 66 is in place in the core shoe, the core and core shoe are placed in a jig and presented to a riveting device which hammers the lower end of the core projections 66 with a large number of light blows, whereby the core projection or foot piece 66 is riveted and expanded into the counter-bore of the hole 64, and the core shoe is thereby firmly united to the core. The core head insulator 57 and the core head 60 are now placed

down against the core shoe and occupy the position shown in Figs. 9 and 10. This assembly is now a magnet spool ready to receive the windings of the magnet between the core head insulator and spool top. These windings are applied in the usual manner and the completed magnet element or magnet spool assembly with the windings on the core is shown in Figs. 11 and 12. The core head insulator is provided for the purpose of affording a convenient means for conveying the inside lead from the coil out to one of the eyelets 62 without liability of injury to its own insulation, or to the insulation of the windings otherwise in contact therewith. The wire is enamel wire, and the end is inserted through the hole in the core head insulator and extends outward between the core head insulator and the core head, being soldered at its outer end to one of the eyelets 62. The other end of the coil wire is run to the other eyelet and soldered to it. The magnet spool assemblies are made rights and lefts, as seen in Figs. 13, 14 and 15. The inside leads from the coils are both connected to adjacent eyelets 62, as shown at the bottom of Fig. 13, and the under sides of which eyelets are united by the connection 70. The outside leads are carried to and soldered on the two eyelets 62, shown at the top of Fig. 13. To these eyelets are secured the upwardly extended lead wires 71. The complete receiver electro-magnet assembly, indicated in a general way by the reference character 72, is shown in Figs. 13, 14 and 15.

The permanent magnet for the receiver consists of two rings 82 shown in Fig. 16, having their north poles at one end as at N, and their south poles at the other end, as at S. A magnet cover 83 consists of a thin piece of sheet zinc nickel plated on its upper side. The magnet elements and the magnet cover are provided with screw holes as shown in Figs. 16 and 17.

The terminal block indicated in a general way by the reference character 86, and shown in Figs. 18, 19 and 20, consists of a body portion 87 of insulating material such as hard rubber or bakelite. It is provided with a screw threaded hole 88 to receive the threaded shank of the cord post 89. It is also provided with two cord terminal holes 90, which receive the terminals of the connecting cord. Vertical holes 91 are provided in the block to receive the terminal pieces or insets 92, which are forced down into the holes 91. Terminal clips 93, provided with holes to receive the bodies of the terminal pieces, are held in position on the upper surface of the terminal blocks by small heads with which the pieces are provided. Each terminal piece 92 is provided with a hole to receive a set screw 94, the cord terminals being received in the holes 90, and the screws

94 being screwed down on the terminals to hold them in place and in good electrical contact.

The receiver is assembled as follows: The receiver box 100, of drawn aluminum, is provided with two holes in its bottom and three holes for the cord terminals and cord post in one side, and two additional holes for the yoke or bail pivots arranged at 90° to the position of the cord post and terminal holes; 75 it is also provided on its outer upper edge with a threaded portion upon which an ear piece is adapted to be screwed. It is first provided with two magnet screws 101, which extend upwardly through the holes in the 80 bottom of the box, whereupon the magnet assembly 72 is lowered into the box, the holes 65 in the core shoes receiving the screws 101. Then the two permanent magnets are inserted with their south poles superposed 85 the one on the other, after which the magnet cover is dropped in place over the screws, nickled side up. Then the nuts 102 are screwed down on the screws 101, and the electro-magnet and permanent magnets are 90 securely held in place in the box. The terminal block is now dropped into place, and the cord post is screwed into the hole 88 therein, whereby it is secured in place in the box. At this time the upper ends of the two 95 lead wires 71 lie close to notches in the ends of the terminal clips 93. By a simple manipulation the ends of these wires are brought to lie in the notches in the terminal clips and are soldered fast. Inasmuch as 100 the cores are made up of laminations their union with the core shoe is not one of great rigidity, and consequently when thus assembled some slight deviation from correct 105 positioning of the pole heads 56 of the cores is possible. To correct this and to secure the accurate positioning of the pole tips with relation to each other, a spool cover 103 is provided with two rectangular openings, of the shape of the core or pole heads, which is 110 forced over the core or head pole to bring them into correct position with relation to each other. It holds itself in position by the tight fit of the cover on the core or pole heads. The instrument is then completed by 115 placing the diaphragm 104 in position and screwing on the ear piece 105.

With receivers of this character a fork or bail 106 is used which is provided with pins 107 which enter holes in the sides of 120 the receiver box, as shown in Fig. 23. The fork or bail 106 is resilient and its pin-tines 107 are held in the holes in the box by the spring pressure of the fork or bail.

This receiver commends itself to the 125 manufacturer by reason of the simplicity of operations by which it is made and its cheapness. It commends itself to the distributor by the uniformity of its electrical and magnetic qualities and it commends it. 130

self to the user by reason of its permanence of construction and durability.

What is claimed is:—

1. A telephone receiver having, in combination, a box having a cord post opening and two terminal openings, a terminal block provided with a tapped opening aligning with the cord post opening in the box, a cord post received in the tapped opening and serving to secure the terminal block to the box, the terminal block also being provided with terminal openings aligning with the terminal openings in the box, set screws in the terminal block adapted to hold external lead wires within the terminal openings, terminal clips on the block, an electro-magnet within the box, and connections between the terminal clips and the electro-magnet.
2. A core assembly for telephone receivers having, in combination, a core having a body portion, an enlarged head or pole piece and a reduced foot, a spool top on the core adjacent to the pole piece of the core, a core head on the core adjacent to the foot, and a core shoe embracing the foot, the foot being riveted in the hole in the core shoe.
3. A core for a telephone receiver magnet consisting of a number of laminations of silicon iron superposed on each other having a body of uniform size, enlargements on the ends of the laminations to form a pole piece at one end of the core body, and a reduced portion at the opposite end of the core body to form a foot or core shoe projection.
4. A magnet element for telephone receivers having, in combination, a core comprising a plurality of iron laminations each having an enlargement at one end and a reduced portion or foot at the other end, a spool top of insulating material having a hole fitting the body of the core and adapted to engage the under side of the pole piece, a core head of insulating material having a similar hole fitting the body of the core located adjacent to the foot thereof, adapted to form the bottom head of the spool, said head being provided with metallic soldering pieces beyond the winding.
5. A telephone receiver having, in combination, a permanent magnet, an electro-magnet magnetically connected with the permanent magnet, a terminal block provided with terminal pieces and terminal clips, a cord post having a reduced shank adapted to pass through a hole in the box and screw into a tapped hole in the terminal block for supporting and securing the latter in place in the box.

VERNON DURBIN.
